UNITED STATES PATENT OFFICE.

ALLEN B. CREEK, OF SAN JOSE, CALIFORNIA.

TYPE-PALLET.

1,207,508.

Specification of Letters Patent.

Patented Dec. 5, 1916.

Application filed May 18, 1916. Serial No. 98,372.

To all whom it may concern:

Be it known that I, ALLEN B. CREEK, a citizen of the United States, and resident of San Jose, in the county of Santa Clara 5 and State of California, have invented certain new and useful Improvements in Type-Pallets; of which the following is a specification.

My invention relates to type pallets, and 10 the object of my invention is to provide a type pallet in which the clamps can be quickly and easily adjusted to any desired number of type, and which will enable the user to quickly and firmly secure the type 15 therein and quickly and easily release the type therefrom.

For a full understanding of my invention and the merits thereof, reference is to be had to the following description and the accompanying drawings, in which:

Figure 1 is a side elevation of my improved type pallet with clamps ready to receive type, and with a part broken away. Fig. 2 is a side elevation of the same with 25 type in position and grasped by the clamps, a part broken away. Fig. 3 is a longitudinal section on A—A of Fig. 5. Fig. 4 is a sectional view on line B—B of Fig. 1. Fig. 5 is a sectional view on line C—C of Fig. 30 1. Fig. 6 is a side view of the triple threaded screw. Fig. 7 is a cross-section on line D—D of Fig. 1. Fig. 8 is a perspective view of one clamp and rack, part being broken away. Fig. 9 is a perspective view 35 of the second clamp and rack, part being broken away. Fig. 10 is an end view of the threaded portion of the triple threaded screw. Fig. 11 is an end view of the triple threaded screw.

Corresponding and like parts are referred 40 to in the following description and indicated in all the views of the drawings by the same reference characters.

Referring now more particularly to the 45 drawings, 1 indicates a case provided with a flange 2 against which type 3 are alined, and a handle 4. Clamps 5 and 6 are slidably mounted on case 1 and are formed as follows: The upper portion of the inner sides 50 7 of said clamps are made smooth to engage type 3 when in use. At 8 and 9 are provided slots adapted to engage the upper and lower sides 1^a and 1^b respectively, of case 1. At 10 in clamp 6 is provided a hole adapted 55 to slidably engage rod 11. 12 indicates a notch formed in clamp 6 to receive one end

of rack 13 and in which rack 13 is rigidly fixed. At 14 is provided a second notch of the proper size to permit rack 15 to move freely therethrough, said rack 15 being rigidly secured in a similar notch as 16 in clamp 5. At 17 in clamp 5 is provided a notch of the proper size to permit rack 13 to move freely therethrough, this construction as described permitting the two clamps to move 60 65 freely backward and forward when actuated as hereinafter described.

Clamp 5 is tapped with a triple thread as indicated at 18 to engage triple thread screw 19, the triple thread being indicated at 19^a. Screw 19 is bored as at 20 in such a manner as to slidably engage rod 11, and a key 21 is positioned in the outer end of said bore for the purpose hereinafter described. Rod 11 is revolvably mounted in 70 75 bearings 22 and 23 respectively in the opposite ends of case 1 and is provided at each end with a thumb-nut as shown at 24 and 25 respectively, the same being held in place by pins 26 and 27 respectively. When 80 clamps 5 and 6 and rod 11 are in position, racks 13 and 15 are held in engagement with pinion 28 by means of legs 29 and 30 on bar 31, bar 31 being secured to the edges 1^a and 1^b of case 1 by screws 32 and 33 respectively.

Pinion 28 is revolvably mounted on pin 34 securely set in case 1 as shown in Fig. 5. Keyway 35 is formed in rod 11 and extends from one end to nearly the center thereof. 90 One side of keyway 35 is notched throughout the major portion of its length as indicated at 36, said notches extending down below the bottom of keyway 35 as indicated at 37, thereby permitting rod 11 to be turned a 95 quarter of a revolution when key 21 is in engagement with one of said notches 36.

My improved type pallet, being assembled, is used as follows, it being assumed that clamp 5 is at all times in engagement 100 with screw 19. Rod 11 is turned into the position shown in Fig. 1 thereby permitting key 21 to move freely in keyway 35, and clamp 5 to move freely back and forth on case 1 a distance equal to approximately 105 one-half of the length of case 1. Rack 15 being rigidly secured to clamp 5 also moves freely back and forth in case 1 and thereby operates pinion 28 which in turn operates rack 13 which is secured to clamp 6. 110 It is evident, therefore, that a movement imparted to one clamp must also move the

other clamp an equal distance and at the same speed but in the opposite direction. If, then, clamps 5 and 6 are moved outwardly toward the ends of the case by pressure against one of them, a line of type may be set in position as shown at 3 and the clamps forced back into loose engagement with said type by pressure against one of them in the opposite direction. In order to 10 tightly clamp type 3 in position it is only necessary now to turn rod 11 in the direction indicated by the arrow perhaps one or two revolutions. The first quarter of a revolution removes key 21 from keyway 35 and places it in one of the notches 37, whereupon screw 19 is caused to turn which in turn forces clamps 5 and 6 to tightly grasp the type positioned therebetween. A quarter turn of rod 11 in the opposite direction 15 again places key 21 in keyway 35, whereupon clamps 5 and 6 may be quickly moved outwardly and the type removed. The triple thread is provided on screw 19 and in clamp 5 in order that clamps 5 and 6 may be moved into and out of engagement 20 with type 3 quickly and without binding by one or two turns of rod 11. If a single thread were used rod 11 would have to be turned a number of times unless the pitch of the thread were increased, which is not 25 desirable as the increased pitch would tend to bind the parts and so destroy the smoothness of its operation.

While I have herein described and illustrated one specific form and size of type pallet, it is understood that I do not wish to limit myself to the specific embodiment shown, as minor changes in form, size and details of construction may be made without departing from the spirit of my invention, as for instance, while I have herein shown and described a tool to be held and operated by hand it may also be adapted for use in an embossing machine without departing from the invention as pointed out in the appended claims.

Having thus described my invention, what I claim as new and desire to secure by Letters Patent, is:

50 1. A type pallet comprising a case, a pair of opposed, coöperating clamp members slidably mounted thereon, a rod revolvably mounted in said case and passing through said clamp members, one of said clamp members being tapped to receive a threaded sleeve, and a sleeve slidably mounted on said rod and threaded to engage said tapped clamp member and means for revolvably engaging said rod and said sleeve.

55 2. A type pallet comprising a case, a pair of opposed, coöperating clamp members slidably mounted thereon, a rod revolvably mounted in said case and passing through said clamp members, and means operatively connected to said rod for imparting motion to said clamp members, said means comprising a sleeve threaded into one of said clamp members and slidably mounted on said rod, and a key attached to the bore of said sleeve, said rod having a groove formed 60 therein adapted to engage said key, and one or more notches formed in the side of said groove adapted to receive said key.

3. A type pallet comprising a case, a pair of opposed, coöperating clamp members 65 slidably mounted thereon, a rod revolvably mounted in said case and passing through said clamp members, one of said clamp members being tapped with a triple thread to receive a threaded sleeve, and a sleeve so slidably mounted on said rod and threaded with a triple thread to engage said tapped clamp member and means for revolvably engaging said rod and said sleeve.

4. A type pallet comprising a case, a pair 70 of opposed coöperating clamp members slidably mounted thereon, a rod revolvably mounted in said case and passing through said clamp members, and means operatively connected to said rod for imparting motion to said clamp members, said means comprising a sleeve threaded into one of said clamp members and slidably mounted on said rod, and an inwardly projecting member attached to said sleeve, said rod having a 75 groove formed therein adapted to engage said projecting member.

5. A type pallet comprising a case, a pair 80 of opposed coöperating clamp members slidably mounted thereon, a rod revolvably mounted in said case and passing through said clamp members, and means operatively connected to said rod for imparting motion to said clamp members, said means comprising a sleeve threaded into one of said clamp members and slidably mounted on said rod, and an inwardly projecting member attached to said sleeve, said rod having a 85 groove formed therein adapted to engage said projecting member and one or more notches formed in the side of said groove adapted to receive said projecting member and extending below the bottom of said groove.

90 In testimony whereof I have hereunto affixed my signature this 13th day of May, 1916.

ALLEN B. CREEK.
